(57) **CLAIM**

The ornamental design for a sleeper sofa, as shown and described.

DESCRIPTION

FIG. 1 is a top, front, right side perspective view of a sleeper sofa in an unfolded configuration, showing my new design; FIG. 2 is a bottom, rear, left side perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a top, front, right perspective of the sleeper sofa shown in a folded configuration; FIG. 10 is a top, front, right perspective view of a mounting component and a left side panel of the sleeper sofa, shown separately to reveal aspects of the design that would not otherwise be apparent in the assembled view; and, FIG. 11 is an enlarged view of portion 11 in FIG. 1. The broken lines in the figures depict portions of the sleeper sofa and form no part of the claimed design. The dash-dot-dash broken lines define the boundary of an enlarged view and form no part of the claimed design.
